UNITED STATES PATENT OFFICE.

EDWARD M. ZERBE, OF LEWISTOWN, PENNSYLVANIA.

HYDRANT.

SPECIFICATION forming part of Letters Patent No. 247,869, dated October 4, 1881.

Application filed April 27, 1881. (Model.)

To all whom it may concern:

Be it known that I, EDWARD M. ZERBE, a citizen of the United States, residing at Lewistown, in the county of Mifflin and State of Pennsylvania, have invented certain new and useful Improvements in Hydrants; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification, and in which—

15 Figure 1 is a front elevation of the hydrant; Fig. 2, a longitudinal section thereof; Fig. 3, a perspective of the valve and its seat detached from the casing; Fig. 4, a cross-section through $x\ x$ of Fig. 2; Fig. 5, a cross section through $y\ y$ of Fig. 2; and Fig. 6 a cross-section through $z\ z$ of Fig. 2, Figs. 5 and 6 representing the ports as closed. Fig. 7 is an enlarged view of the lower part of Fig. 2.

25 My invention relates to hydrants; and it consists in the construction and the combination of parts hereinafter particularly described, and then sought to be specifically defined by the claims.

30 In the accompanying drawings, the letter A indicates the top casing, and B the lower casing, one being passed into the other (screwed if desired) and further secured together by a screw, a , passed through the outer casing into or against the lower casing. The recessed top 35 C is fastened by screws or other means to the casing A, and into its recess the upper end of the hollow valve-rod D fits, that end of the rod being a T, detachable from the other section of the rod.

40 A spout, E, screws into the T-head of the rod, communicating with the interior of the same, and passes through a slot, F, formed in the casing, and in which it is free to play from right to left.

45 Onto the lower end of rod D there is screwed the valve G, which is prevented by a thumb-screw from turning on the rod. This valve has four or more openings in its sides for the escape of waste water, and several openings in 50 its bottom for the inlet of water into the hollow valve-rod, and is provided on its outside with

two or more lugs, H. The valve G fits into the valve-seat J, which is constructed with a threaded lower exterior, so that it may be screwed into a box or extension, K, and with 55 recesses L at its top, into which the lugs H of the valve may fit, so that when they are turned till they strike against the shoulders of the recesses they will then turn the valve-seat with the valve, either connecting it to or disconnecting it from the extension K, according as the parts are being put to their places for operation or taking therefrom for repairs.

Theseat is provided with openings in its sides to correspond with those in the sides of the 65 valve, for the escape of wastewater which passes off through openings formed in the extension K next to the valve, as clearly shown in Fig. 2 of the drawings; and it is also provided with openings in its bottom for the inlet of water to 70 the valve. It is further formed with a flange, M, that is intended to bear down upon an elastic washer, c, which rests upon the seat N of the extension K, so that a close joint will be made between the extension and valve-seat. 75

The openings in the sides of the valve and valve-seat are so arranged with reference to each other that when the valve is turned to let on the supply of water the waste holes in the valve and its seat will be completely closed before any water is let on, so that there will be 80 no waste of water while it is being drawn.

The valve and its seat are held together so that the bottom of the former will not come in contact with the bottom of the latter, and preferably so that the fans of the recesses in the seat and fans of the lugs to the valve will not rub against each other, whereby the friction caused by those parts rubbing together is obviated and the working of the parts made 90 easier. That end I attain by making the outer circumference of the valve and inner circumference of its seat slightly tapering, as seen in Fig. 2.

The valve and its seat are held together by 95 a bolt, O, cast with the valve and made with a square shoulder, d, to pass through a square opening in the washer P, which has openings corresponding to those in the base of the valve, and a suitable packing to fit against the sides 100 of the seat; a threaded portion, e, to receive a nut, Q, which holds the washer against the

valve; a rounded portion, *f*, which passes through a corresponding opening in the base of the valve-seat and permits the valve to turn without turning the seat; a square shoulder, *g*, which passes through a corresponding opening in the valve-plate *R*, which has openings corresponding to those in the base of the seat and through a metallic washer, *S*, whereby the plate and washer are caused to turn with the valve; and, finally, a threaded portion, *b*, which receives a nut, *T*, that presses an elastic washer, *i*, against the metallic washer *S* and holds the plate *R* against the valve-seat and the valve and its seat together.

15 The washer *P* is made with a peripheral recess to receive an elastic fastening, *j*, to make a close joint between the valve and the sides of its seat. The washer is detachable in order that the packing may be the more snugly fitted

20 in the recess thereof, and be clamped between the washer and bottom of the valve.

In operation, when the water is to be turned on, the spout *E* is grasped and pushed to one side, which movement turns the hollow rod *D* and carries with it the valve *G* and plate *R*, bringing the openings in both opposite to those in the base of seat *J*, so that the water which is received into the extension *K* through a lateral pipe from the source of supply, passes up

25 through the valve and hollow rod to and through the discharge-pipe. When the water is to be turned off the spout is pushed back to its first position, which movement closes communication between the valve and its seat, and

30 excludes water therefrom. The waste water now passes off through the openings in the

sides of the valve-seat and extension *K*, and this feature renders the hydrant anti-freezing.

When the hydrant needs repairs the top is detached from the upper casing and the rod *D* 40 then turned till the valve and its seat are unscrewed from the extension *K*, when the detached parts are lifted out from the casings *A* and *B*, which remain undisturbed in their places.

The recess in the top of the hydrant serves 45 as a guide for the rod *D*, to steady the same.

Having described my invention, what I claim is—

1. The valve *G*, provided with lugs *H* and bolt *O*, cast therewith and provided with shoulders *d* *g*, smooth rounded portion *f*, and threaded portions *e* *h*, in combination with seat *J*, provided with recesses *L*, washer *P*, plate *R*, and nuts *Q* *T*, the valve and its seat having waste-openings arranged as described, substantially as and for the purposes specified.

2. The tapering valve *G*, provided with lugs *H* and bolt *O*, in combination with tapering seat *J*, provided with recesses *L*, plate *R*, and nut *T*, substantially as set forth.

3. The combination of seat *J*, provided with recesses *L* and flange *M*, valve *G*, provided with lugs *H* and bolt *O*, plate *R*, and extension *K*, provided with seat *N*, and elastic packing *e*, interposed between flange *M* and seat *N*, substantially as and for the purpose specified.

In testimony whereof I affix my signature in presence of two witnesses.

EDW. M. ZERBE.

Witnesses:

I. DON HARVEY,
A. P. BOEHNER.

It is hereby certified that in Letters Patent No. 247,869, granted October 4, 1881, to Edward M. Zerbe, for an improvement in "Hydrants," the word "faees," in lines 86 and 87, on page 1 of the printed specification attached to and forming a part of said Letters Patent, was erroneously printed "fans;" that the proper corrections have been made in the files and records of the Patent Office, and are hereby made in said Letters Patent.

Signed, countersigned, and sealed this 18th day of October, A. D. 1881.

[SEAL.]

A. BELL,

Acting Secretary of the Interior.

Countersigned:

E. M. MARBLE,
Commissioner of Patents.
